(57) **CLAIM**

The ornamental design for a tire cover, as shown and described.

DESCRIPTION

FIG. 1 is a side perspective view of the tire cover showing four evenly spaced grommets and four tabs.

FIG. 2 is a front view of the front of the tire cover showing four evenly spaced grommets.

FIG. 3 is a rear view of the rear of the tire cover showing how the tire cover snugly fits around a tire belonging to heavy warehouse equipment; and,

FIGS. 4-7 are side views of the four sides of the tire cover. The broken lines on the tire cover represent the stitching on the tire cover and does not form part of the claimed design. The broken lines inside the tire cover represent the environment of a tire well and do not form part of the claimed design.

1 Claim, 5 Drawing Sheets
